(57) **CLAIM**

The new and ornamental design for a mesh back task chair, as shown and described.

DESCRIPTION

FIG. 1 is a perspective view of a mesh back task chair showing my new design;

FIG. 2 is a view in front elevation of the mesh back task chair of FIG. 1;

FIG. 3 is a view in rear elevation of the mesh back task chair of FIG. 1;

FIG. 4 is a view in left side elevation of the mesh back task chair of FIG. 1;

FIG. 5 is a view in right side elevation of the mesh back task chair of FIG. 1;

FIG. 6 is a top plan view of the mesh back task chair of FIG. 1;

FIG. 7 is a bottom plan view of the mesh back task chair of FIG. 1;

FIG. 8 is a bottom plan view of the mesh back task chair of FIG. 1 with the support base removed for clarity;

FIG. 9 is a bottom plan view of the mesh back task chair of FIG. 1 with the support base, control mechanisms, and arms removed for clarity;

FIG. 10 is a perspective view of a mesh back task chair showing my new design with fixed-height arms;

FIG. 11 is a view in front elevation of the mesh back task chair of FIG. 10;

FIG. 12 is a view in rear elevation of the mesh back task chair of FIG. 10;

FIG. 13 is a view in left side elevation of the mesh back task chair of FIG. 10;

FIG. 14 is a view in right side elevation of the mesh back task chair of FIG. 10;

FIG. 15 is a top plan view of the mesh back task chair of FIG. 10;

FIG. 16 is a bottom plan view of the mesh back task chair of FIG. 10;

FIG. 17 is a bottom plan view of the mesh back task chair of FIG. 10 with the support base removed for clarity; and,

FIG. 18 is a bottom plan view of the mesh back task chair of FIG. 10 with the support base, control mechanisms, and arms removed for clarity.

The particular mesh fabric of the chair back is shown for illustrative purposes only and forms no part of the claimed design.
